[57] CLAIM

The ornamental design for a guitar pick, as shown and described.

DESCRIPTION

FIG. 1 is a perspective view of a guitar pick, showing my new design;

FIG. 2 is a front elevational view, the rear elevation being a mirror image;

FIG. 3 is a top plan view;

FIG. 4 is a left side elevational view, the opposite side being a mirror image;

FIG. 5 is a bottom plan view;

FIG. 6 is a perspective view of a guitar pick, showing my alternate new design;

FIG. 7 is a front elevational view, the rear elevation being a mirror image;

FIG. 8 is a top plan view;

FIG. 9 is a left side elevational view, the opposite side being a mirror image; and,

FIG. 10 is a bottom plan view.

FIG. 1

FIG. 3

FIG. 2

FIG. 4

FIG. 5

FIG. 6

FIG. 7

FIG. 9

FIG. 10
